HENRI ARNOLD JOHANNES DE BIJLL NACHENIUS, OF HAARLEM, NETHERLANDS.

BRAKING DEVICE FOR VESSELS PROPELLED BY GAS DISCHARGED BELOW THE WATER LEVEL.

Application filed July 3, 1922. Serial No. 572,585.

To all whom it may concern:

Be it known that I, HENRI ARNOLD JOHANNES DE BIJLL NACHENIUS, a subject of the Queen of the Netherlands, residing at 5 Haarlem, Netherlands, have invented certain new and useful Improvements in Braking Devices for Vessels Propelled by Gas Discharged Below the Water Level, of which the following is a specification.

10 This invention relates to an improvement in or modification of vessels adapted to be propelled by gas (usually air) discharged below the water level with a pressure which does not appreciably exceed the 15 water pressure at the outlet, and having a substantially plane, upwardly inclined stern face for guiding the rising gas bubbles.

As a matter of course the gas (air) which normally raises to the water level along 20 the usual inclined stern surface extending through the full or the greater part of the width of the vessel, may also be allowed to escape along the bow so as to cause the vessel to go astern. This, however, is only 25 possible as long as the vessel does not go ahead, for otherwise the air discharge without overpressure would, even if it were discharge in the direction of movement of the 30 vessel and in substantially parallel relation with the bottom, immediately move backwards with respect to the vessel owing to the very considerable resistance offered by the water, or, stated in other words, the ship would simply slide over the stratum of air.

35 In view of this circumstance it is found difficult to promptly stop a vessel arranged for the application of the new method, or to suddenly reduce its speed. The primary object of this invention is to meet this difficulty.

This invention essentially consists in providing the inclined stern surface of the vessel with one or a plurality of brake plates rotatable about transverse shafts and adapted 45 to normally lie flat against the plane stern surface but, if necessary, to be lowered separately or conjointly so as to produce a rapid braking effect by its reaction. As the inclined stern surface extends through the entire or the greater part of the ship's width, the hinged connection of the plates does not offer technical difficulties although said plates have to stand heavy strains when in 50 action.

Preferably the brake plates are associated 55 with counterweights in such a manner that they always have a tendency to move into contact with the rear surface. The said counterweight is suitably made in the form of a piston movable in an upright cylinder 60 so that it is raised and the lowering of the brake plates initiated when pressure medium is admitted to the bottom side of the piston; in this case the water pressure causes the plate to completely swing out, 65 suitable means being provided to prevent said plate from further backward movement after having reached its vertical position. In its highest position the piston-like counterweight is braked, for instance, by 70 springs or preferably by an air buffer.

The described braking device also readily lends itself to the steering of the vessel. If, for instance, three brake plates are provided side by side, the vessel may be steered 75 to port or to starboard by the lowering of the port-plate or of the starboard-plate, respectively; concurrently the discharge of gas at the side where the brake plate is operative may be cut off and thereby the 80 turning moment increased.

Also without cutting off the discharge of gas at one side the turning moment may be increased to a considerable extent. In ships of the type referred to the bottom 85 and the inclined stern surface are generally provided on their lower side with a plurality of ribs extending through substantially the entire length of the ship and serving the purpose of guiding the air and preventing same from escaping sideways. When employing three brake plates, for instance, four of such ribs may be provided whereby three inverted channels are formed on the lower side of the bottom, one brake plate being arranged in each channel, which itself may be subdivided by longitudinal ribs. Now, in accordance with the invention both extreme ribs may be recessed or cut away through a suitable distance immediately in 100 front of the shafts of the brake plates from which the following results will be obtained: If the vessel when going ahead is to turn to starboard, the starboard-brake plate is lowered without, however, the discharge of air on the starboard side being cut off. The air escaping astern through the port-channel and the resistance to the 105

water offered by the starboard-brake plate produce a turning moment in the desired direction. At the same time, however, the air which rises through the starboard-channel 5 but which is prevented by the starboard-brake plate from escaping astern has freedom to escape sideways through the said recess in the starboard-air guiding rib, that is to say, to starboard, so that it rises to the 10 water level along the ship's side, thus exerting a pressure thereon and producing a current of water substantially at right angles to the ship's side, which current by its reaction on the starboard-side of the stern part 15 of the ship considerably assists in turning the vessel to starboard.

The method of steering just described has the advantageous feature that it can be satisfactorily applied even when the ship 20 has no steering way; under like circumstances an ordinary rudder would not have any effect, as is well known.

The invention will now be described with reference to the accompanying drawings, 25 which illustrate by way of example an embodiment of the invention, and in which:

Figure 1 shows a diagrammatic longitudinal section of the stern part of a vessel in accordance with the invention.

Figure 2 shows on a reduced scale the rear elevational view of the same with its brake plates vertically depending and

Figure 3 shows a diagrammatic view of a modified mechanism for actuating the brake plates.

a and *b* designate two decks, *c* the inclined stern surface extending through the greater part of the width of the ship, *d*, *e*, *f*, *g* four air guiding ribs secured on the underside of 40 the bottom of the boat and of the stern surface. Hinged to the rear end of the surface *c* are three brake plates *h*, *i*, *j*; these plates are rotatable about horizontal shafts which are suitably supported and each arranged between two ribs. Each plate is hinged to a chain 1 running upwards through a hole in the ship's bottom and through a pipe *o* provided with chain wheels *m*, *n* and secured to a piston *q*, which, while 45 acting as a counterweight, is provided in a vertical cylinder *p*. Compressed air can be admitted to the bottom of the cylinder through a pipe *r*. When the plate depends vertically the piston *q* assumes its highest 50 position which, in the example shown, is determined by springs *s*; if the brake plate lies flat against the inclined rear surface *c* the piston *q* is in position near the lower cylinder cover. If the piston through the 55 action of compressed air is raised from its lowermost position, the brake plate descends by gravity through a corresponding distance; when the vessel is going ahead, the plate is quickly forced into its vertical position owing to the pressure of the water.

The springs *s* may suitably be replaced by an air buffer; in this case cylinder *p* can be made to act both as a press- and as a brake-cylinder.

Instead of lowering the brake plates by the action of pressure medium and allowing said plates to rise into their inoperative positions in contact with the inclined stern surface under the influence of gravity, the arrangement may be reversed. Reference 70 is made to Figure 3, in which the chains 1, secured with one end to a brake plate, are attached with the other end to a yoke 3 on the rod 2 of an ordinary piston movable in a cylinder 1', said rod having a projection 4 which when raised to a level responsive to the inoperative position of the brake plate coacts with a pawl 5 so as to lock the rod 2 with its associate parts. If the brake plate in this arrangement is to be moved from its 80 braking position into its inoperative position, pressure medium, for instance from the compressed air storage reservoir of a Diesel motor, is admitted to the bottom side of cylinder 1 through a pipe 6 provided 90 with a valve (not shown). For lowering the plate into its braking position all that is required is releasing pawl 5 and exhausting the air below the piston in cylinder 1, for which purpose an outlet pipe 7 with a 95 valve (not illustrated) is provided. The said valves and the pawl 5 are preferably interconnected and adapted to be actuated from the bridge of the vessel. As these means do not form part of the present invention they have not been illustrated in further detail.

Provided on the back side of the brake plates are strengthening webs *t*. The extreme strengthening ribs of plates *h* and *j* 105 are preferably so arranged, or so high, as to fill up the recesses of the extreme fixed air guiding ribs when the brake plates lie flat against the ship.

What I claim is:—

1. An improvement in or modification of a vessel adapted to be propelled by gas discharged below the water level and having a substantially plane, upward inclined stern face for guiding the rising gas bubbles, characterized thereby that the said inclined stern surface is provided preferably near its upper part with a braking device comprising one or more brake plates which are rotatable about a transverse axis, said plate or plates being adapted normally to lie flat against the stern surface and when required to be separately or conjointly lowered into the water.

2. A vessel as claimed in claim 1 and provided with longitudinal gas guiding ribs on the lower side of the bottom and of the inclined stern surface, characterized thereby that the extreme ribs on the inclined stern surface are cut away through a suitable dis-

tance immediately in front of the brake plates.

3. A vessel as claimed in claim 2, characterized thereby that the brake plates are provided with strengthening webs adapted when the brake plates lie flat against the rear surface to fill up the recesses of the fixed gas guiding ribs.

4. A vessel as claimed in claim 1, characterized thereby that the brake plates are each connected through a chain or like element with a counterweight movable as a

piston working within an upright press- or brake-cylinder.

5. A vessel as claimed in claim 2 characterized thereby that the brake plates are each connected through a chain or like element with a counterweight movable as a piston working within an upright press or brake cylinder.

In testimony whereof I affix my signature.

HENRI ARNOLD JOHANNES de BIJLL NACHENIUS.
